UNITED STATES PATENT OFFICE.

JOSEPH KOSATKA, OF CHICAGO, ILLINOIS.

EDGE-GUIDE FOR SEWING-MACHINES.

No. 873,246.

Specification of Letters Patent.

Patented Dec. 10, 1907.

Application filed October 27, 1906. Serial No. 340,804.

To all whom it may concern:

Be it known that I, JOSEPH KOSATKA, a citizen of the United States, residing at Chicago, in the county of Cook and State of Illinois,

5 have invented certain new and useful Improvements in Edge-Guides for Sewing-Machines, of which the following is a specification, reference being had therein to the accompanying drawing.

10 My invention relates to an edge-guide for sewing machines to be used in connection with a sewing machine of the ordinary and usual construction, in making stitched edges to garments, all kinds of welt seams, closed 15 seams, piping, and in sewing on binding, tapes, and cords.

While by the employment of my invention better results than at present obtained may be had in regard to all of the above operations, 20 it is particularly adapted to the making of stitched edges, which to do well is known to all tailors to be one of the most difficult things in the art.

Heretofore in making stitched edges to 25 garments, after the two pieces of material with the linings, canvas, etc., which are to form the edges, have been sewed together in the usual manner, the seam thus made is rolled out by hand in a manner well understood. 30 stood in the art and then basted to hold the two edges in position while being stitched on the machine. In the most expensive garments the greatest care must be used to force the seam out as far as possible and at 35 the same time evenly throughout its entire length, when it is then basted, using stitches close together and usually two or more rows of basting are put in. At the present time in order to push out this seam the material 40 has first to be rolled between the fingers, which requires a great deal of pressure and is a very laborious operation. For this reason it is difficult to get this work done by those who are capable of doing it correctly 45 as it also makes the worker's fingers sore and painful.

The fit of the garment depends very largely upon the manner in which the edges are stitched and this particular feature of the 50 work is considered of importance. If the seam is not driven out to the very edge at every point throughout its entire length the garment will not hang well, and folds and wrinkles will appear after the edges have 55 been stitched; and very often the edges will flare. In order to reduce these wrinkles and

folds the edges will have to be pressed with a hot flat-iron, and unless the pressing is properly done the wrinkles and folds will again appear, and if done with the modern high pressure machines the edges will flare.

By the employment of my invention, in a manner to be hereinafter described, the seam is properly driven out to the edge of the material uniformly throughout its length, 65 so that the stitching will be at uniform distance from the seam, doing away with the rolling of the material by the fingers and the usual basting.

In the accompanying drawings—Figure 1 70 is a top plan view of a device embodying my invention, mounted upon the table of a sewing machine; Fig. 2 is a side view in elevation of the same, showing also certain parts secured to the under side of the table; Fig. 3 is 75 a view on the line 3—3 of Fig. 2, parts being shown in section and parts in side elevation; Fig. 4 is a detail cross-sectional view of the holder; Fig. 5 is a cross-sectional view on the line 5—5 of Fig. 4; Fig. 6 is a cross-sectional 80 view on the line 6—6 of Fig. 4; Fig. 7 is a plan view of a raising plate which may be employed; and Fig. 8 is a view showing the operation of my invention upon the sewed edges.

Like figures refer to the same parts throughout all the drawings.

In the drawings, 9 is the table of a sewing machine of the usual or ordinary type, 10 a metal spool-shaped standard which is longitudinally bored to receive a cylindrical guide post 11, which, together with all of the other parts is of metal, and is provided with threads adapted to engage a screw-threaded aperture in the base plate 12. The standard 90 10 is also bored transversely to receive a horizontal cylinder 13, which is of a suitable thickness to give the required strength for the purposes hereinafter set forth and is secured thereto by the binding screw 14. The 100 base plate 12 carries two guides 15 and 16 on opposite sides of the standard 10, and a post 17, at one side of the line of the cylinder 13, the guides 15 and 16 being adapted to loosely receive binding rods 18 and 19, respectively, 105 which also pass through the base plate 12 and table 9 as is clearly shown in Fig. 3. The post 17 supports a stop 20 which is slotted to receive the adjusting screw 21 which binds it to the said post. The cylinder 13 is provided at its ends with plugs 22 which are rigidly secured thereto by the screws 23. The 110

plugs are of suitable thickness to furnish the proper strength required and are provided with squared apertures to loosely receive the square rod 24, to which an arm 25 is rigidly secured by means of the bolt 26 and the nut 27. The cap 28 of the standard is provided with ears 29 and 30 through which the ends of the binding rods 18 and 19 pass and receive the nuts 31 which when set rest and bear upon the said ears. The cap is recessed or hollowed out on its under side and carries in such recess a spring 32 which in the form shown is bowed and connected by screws 33 and bears upon a plug 34 which in turn bears upon the rod 24 to rigidly hold it in operative position.

The cylinder 13 at its upper side is provided with an aperture adapted to receive the plug 34, which is preferably cylindrical in shape and fits snugly in the longitudinal bore of the standard 10 with its upper and lower flat faces in engagement with the spring 32 and the rod 24, respectively. The binding screw 35 holds the rod 24 in frictional engagement with the plugs 22 and thereby assists in securely holding the rod 24 in operative position. The rod 24 carries an adjustable collar 36 which may be securely held in position by an adjusting screw 37, the purpose of which will hereinafter appear. The standard 10 with its associated parts is adapted to be raised, for a purpose to be more clearly set forth hereinafter, by the employment of one or more raising plates 38, adapted to be inserted between the standard 10 and base 12, and each of which is slotted as at 39 to engage the guide post 11 and is held in position by a set screw 40 engaging an open slot 41 in a projection thereof. The lower ends of the binding rods 18 and 19 pass through the ends of a cross beam 42, which is reduced at its ends as shown in Fig. 3, and receive nuts 43 which when in operative position bear upon the ends of the said cross beam.

The outer end of the arm 25 is adapted to receive a holder in the form of a hollow cylinder 44 which is held in rigid engagement therewith by means of the binding screw 45. The holder 44 is provided at its ends with plugs 46 and 47 which are secured thereto by means of the screws 48 and are provided with apertures adapted to loosely receive the square rod 49, which is adjustably held in engagement with said plugs by means of the binding screw 50. The rod 49 carries a coil spring 51 which reacts at one end against a pin 52 on the rod and at the other end against the plug 46. The plug 47 is recessed as at 53 to clear the pin 52 when the rod 49 is withdrawn from the holder 44. The rod 49 carries two adjustable collars 54 and 54', the particular uses of which will hereinafter more fully appear, and which are secured to the rod 49 by means of adjusting screws 55. A

supplemental coil spring 56 surrounds the rod 49 between the plug 47 and the collar 54', said spring not being normally under tension. The rod 49 carries an edge presser or guide 57 which is detachably fastened thereto by means of screws 58. The edge guide may be of any suitable form and preferably is provided at its free end with a yoke 59 adapted to receive a wheel 60 which is free to revolve upon its axle 61. The gage 62 and adjusting screw 63 and the throat plate 64 are of any suitable form and construction.

A shaft 65 is journaled in suitable hangers 66 attached to the under side of the table, and carries at its inner end a cam 67 which bears upon the cross beam 42. At its outer end the shaft is provided with a collar 68 secured by means of a screw 69 or other suitable means. The collar has a depending hollow elbow 70 in which a leg 71 is secured at a right angle to the shaft 65. The leg 71 at its lower extremity is bent at right angles in the direction parallel to the length of the shaft 65 and carries a foot rest 72 which rocks thereon and is prevented from slipping off by means of the pin 73. A coil spring 74 has one of its ends attached to the leg 71 and the other end to the under side of the table 9 in any suitable manner, and a second coil spring 75 is attached to the leg at the same point and has its other end secured to the toe of the foot rest 72.

The shaft 65 extends beyond the collar 68 and carries a ratchet wheel 76, secured thereto in any suitable manner, with which a pawl 77 coacts to hold the shaft 65 against turning in one direction, the pawl being supported in a hanger 78 attached to the under-side of the table 9. One end of a chain 79 is attached to the free end of the pawl, its other end being connected to the toe of the foot-rest 72. A stop 80 is secured to the under-side of the table to limit the movement of the leg under the tension of the spring 74.

As material of many different thicknesses 110 may be stitched with my device, in order to raise the wheel 60 so that it will properly engage and force out the seam which is to form the edges to be stitched, one or more of the raising plates 38 may be inserted between the base plate 12 and the standard 10, according to the thickness of the material.

When the wheel 60 has been properly adjusted the operator places his foot upon the foot rest 72 and moves the leg 71 forward until it occupies a position shown in dotted lines in Fig. 3. The leg 71 thus rocks the shaft 65 and the cam 67 presses down the cross beam 42. As the cross beam 42 is pressed down the cap 28, which is in operative connection with it by means of the binding posts 18 and 19, is likewise drawn down to force the spring 32 down hard upon the plug 34 which in turn bears upon the rod 24 and thus holds it in rigid engagement with 130

the plugs in the cylinder 13. When the leg 71 is thus moved forward far enough to produce the required pressure upon the cross beam 42, it is held in this position by means 5 of the pawl 77 which engages the ratchet wheel 76. In order to release the parts, the operator rocks the foot-rest on its pivot, when the chain 79 withdraws the pawl 77, and the spring 74 retracts the leg to the position shown in full lines releasing the cross-beam from the pressure of the cam and permitting the spring 32 to raise the cap and release the pressure on the rod 24. When the parts are thus released the arm 25 and its associated parts may be swung out of operative position by turning the standard 10 on the post 11, as shown in dotted lines in Fig. 1. When the operator desires to use my device he swings the arm back again 15 until it comes in contact with the stop 20 which is so adjusted that it stops the arm with the wheel 60 in the correct position for use.

In order that my invention may work to the best advantage with certain kinds of material, such as thin cloth, it is desirable to maintain rigidity of the several parts, and the construction disclosed has proved to be most satisfactory. While it is possible to 25 secure the requisite rigidity of the parts when in operative position, in ways other than that disclosed, I have found that the means as illustrated by the accompanying drawings is satisfactory as by the use of it 30 the operator may secure the requisite rigidity with no loss of time. When thicker material is employed, satisfactory results may be obtained by releasing the binding screw 50, adjusting the wheel 60 to the proper 40 position with reference to the gage 62 in which it is maintained by the spring 51 and then sliding the collar 54 into engagement with the holder 44 and securing it to the rod 49 by the adjusting screw 55 which thus prevents 45 the wheel 60 under the action of the spring 51 upon the rod 49 from being pushed nearer to the gage than the predetermined distance. Of course as the material is stitched the wheel may give a little, due to 50 the unevenness in the seam, but this is controlled by the spring 51 which at once forces the wheel back to its proper position. The spring 56 is so adjusted that it is not brought 55 into use by the collar 54' until the spring 51 is contracted to a certain extent and then the spring 56 aids in holding the edge-guide up to the work. The adjusting of the collar 54' controls the point at which the spring 56 is brought into service.

60 I have illustrated one use of my invention by showing its application to making stitched edges. In Fig. 8 the edge-guide presses against the seam 86 made by sewing the two pieces of material 87 together and as the material is fed along the throat plate 64 the

wheel forces the seam out and presses it against the gage 62 and in position for the needle 85 to stitch the two edges uniformly.

Having described my invention what I claim as new and desire to secure by Letters 70 Patent of the United States, is—

1. In a device of the class described, the combination with a base plate, a guide post, a standard adapted to revolve thereon, a cylinder disposed transversely of the standard, and an edge-guide carried thereby and adapted to press out the seam of the material. 75

2. In a device of the class described, the combination with a base plate, a guide post, a standard adapted to revolve thereon, a 80 gage an edge-guide on the standard, and adapted to press out the seam of the material toward the gage, and a stop on the base plate for the edge-guide.

3. In a device of the class described, the 85 combination with a base plate, a guide post, a standard adapted to revolve thereon, an edge-guide on the standard and adapted to press out the seam of the material, a stop on the base plate, and means for adjusting the 90 stop.

4. In a device of the class described, the combination with a base plate, a guide post, a standard adapted to revolve thereon, an arm carried by the standard, an adjustable 95 holder carried by the arm, and an edge-guide carried by the holder and adapted to press out the seam of the material.

5. In a device of the class described, the 100 combination with a base plate, a guide post, a standard adapted to revolve thereon, an edge-guide on the standard, and a raising plate for the standard.

6. In a device of the class described, the combination with a base plate, a guide post, 105 a standard adapted to revolve thereon, an edge-guide on the standard, and a raising plate for the standard having a slot to engage the post.

7. In a device of the class described, a 110 standard, an arm on the standard, an adjustable holder on the arm, a spring on the holder, and an edge-guide carried by the holder and against which and the holder the spring is adapted to react.

8. In a device of the class described, a standard, an arm on the standard, a holder on the arm, an edge-guide carried by the holder, and a spring reacting against the holder and edge-guide. 115

9. In a device of the class described, a standard, a gage, a holder carried by the standard, a spring pressed edge-guide carried by the holder, a spring between the edge-guide and the holder, the edge-guide and gage co-operating to press out a seam, and means for adjusting the action of the springs. 125

10. In a device of the class described, a standard, a gage, a holder carried by the 130

standard, a rod in the holder and carrying an edge-guide, a spring in the holder acting upon the rod, a supplemental spring between the holder and the edge-guide, the edge-guide and gage coöperating to press out a seam, and means for adjusting the action of the springs.

11. In a device of the class described, a standard, a gage, a holder carried by the standard, a rod in the holder and having an edge-guide, a spring reacting between the holder and rod in the direction of the gage, an adjustable collar limiting the action of the spring, a spring between the holder and edge-guide, and an adjustable collar adapted to act on said latter spring.

12. In a device of the class described, a revolving standard, an edge-guide on the standard, a cap adapted to lock the standard in position, and means to positively raise and lower the cap.

13. In a device of the class described, a revolving standard, an edge-guide adjustable in the standard, a cap on the standard adapted to lock the edge-guide and standard together, and means to positively raise and lower the cap.

14. In a device of the class described, a standard, an edge-guide on the standard, a cap on the standard adapted to lock the edge-guide and the standard together, binding rods on the cap, and means to operate the binding rods.

15. In a device of the class described, a standard, an edge-guide on the standard, a cap on the standard adapted to lock the edge-guide and the standard together, binding rods on the cap, a shaft, a cam on the shaft coacting with the binding rods, and means to operate the shaft.

16. In a device of the class described, a standard, an edge-guide on the standard, a cap on the standard adapted to lock the edge-guide and the standard together, binding rods on the cap, a shaft, a cam on the shaft coacting with the binding rods, and means to operate the shaft and to lock it in operative position.

17. In a device of the class described, a standard, an edge-guide on the standard, a cap on the standard adapted to lock the edge-guide and the standard together, binding rods on the cap, a shaft, a cam on the shaft coacting with the binding rods, a leg to operate the shaft, a pawl to lock the shaft in position, a foot-rest on the leg, and a connection between the foot-rest and pawl.

18. In a device of the class described, a standard, an edge-guide on the standard, a cap on the standard adapted to lock the edge-guide and the standard together, binding rods on the cap, a shaft, a cam on the shaft coacting with the binding rods, a spring-actuated leg on the shaft, a pawl to lock the shaft in position, a foot-rest pivoted on the leg, a spring holding the foot-rest in normal position, and a connection between the pawl and foot-rest to release the former when the latter is actuated against its spring.

19. In a device of the class described, the combination with a base plate, a guide post, a standard adapted to revolve thereon, a raising plate for the standard, a cylinder disposed transversely of the standard, a rod adjustably carried thereby, a stop against which the rod rests in operative position, an arm on the rod, a holder on the arm, means for adjusting the holder, and an edge-guide on the holder.

20. In a device of the class described, the combination with a base plate, a guide post, a standard adapted to revolve thereon, a raising plate for the standard, a cylinder disposed transversely of the standard, a rod adjustably carried thereby, a stop against which the rod rests in operative position, an arm on the rod, a holder on the arm, means for adjusting the holder, and a spring-actuated edge-guide on the holder.

In testimony whereof I affix my signature in presence of two witnesses.

JOSEPH KOSATKA.
